UNITED STATES PATENT OFFICE

2,303,851

BRAKE PISTON PACKING CUP REMOVING
DEVICE

Joseph R. Lindroth, Galesburg, Ill.

Original application January 23, 1939, Serial No. 252,286. Divided and this application December 26, 1940, Serial No. 371,664

1 Claim. (Cl. 29—85)

My invention relates to a device for removing the packing cups on the heads of the pistons of "AB" brake cylinders, the type employed on railroad freight cars, namely the annular cap or cup member which fits over the entire outer face of the piston-head and holds the packing elements in place; the invention having for its object the provision of a device whereby the snugly fitting packing cup may be easily removed without causing injury to the cup or to the piston-head.

The objects and advantages of my invention will be readily comprehended from the detailed description of the accompanying drawing wherein:

Figure 1 is a top view in perspective of my improved device with a portion of the hand lever broken away.

Figure 2 is a bottom view in perspective of the device with a portion of the hand lever broken away.

Figure 3 is a vertical sectional view of an air cylinder piston, (shown mounted in my improved piston dismantling apparatus disclosed in my pending application Serial No. 252,286) and my cup removing device applied thereto.

My invention is especially intended for removing the packing cup on the pressure head of the piston of an "AB" air brake cylinder in order to permit proper inspection, cleaning and renewal of the packing ring or member which carries the usual lubricant saturated felt ring. These packing cups are formed of thin sheet metal and provided with a beaded or curled perimeter adapted to snap into recesses in the perimeter of the piston-head after the packing elements have been put into place; the cups effecting a very snug fit about the piston-heads which make their removal rather difficult. In order to remove these cups it has frequently been necessary to employ a tool or bar whereby the cups could be pried from the head, which often resulted in damaging the cups and the packing elements as well as the piston-head and making further use impossible. This method also consumed considerable time and labor during the frequent periodical inspections, cleaning and lubricating operations. My improved cup removing device is designed to eliminate the difficulties mentioned and to enable removal of the cups to be quickly made.

The pressure head 15 of the piston, to which the sleeve 16 is secured, is recessed and flanged on its outer perimeter to receive the channeled metallic ring 17, which seats on the flange 18, and to receive the curled perimeter of the metal-

lic cap or cup member 19 which snaps into the recess in the perimeter of the piston head, as shown in Figure 3; one of the channels or grooves in the ring 17 is provided with a lubricant saturated felt ring as indicated at 20.

It is understood, of course, that the pistons must be completely removed from the cylinders to permit thorough inspection, cleaning and lubrication and suitable means must be provided to completely dismantle the pistons, for example apparatus of the nature shown in Figure 3, which constitutes the subject matter of my pending application Serial No. 252,286, whereby the piston may be properly held in upright position by means of suitable jaw members which engage the non-pressure head 21 of the piston.

My improved packing cup removing device consists of a substantially semi-circular member 22 provided with an inwardly disposed flange 23 which is adapted to engage in the vacant channel or groove 24 of the lubricator or channeled ring 17 disposed beneath the curled perimeter of the packing cup 19, as shown in Figure 3. As member 22 is substantially semi-circular, it may be readily slid edgewise about the packing cup 19 with its flange 23 extending into the vacant channel or groove of the double channeled ring or lubricator 17, as shown in Figure 3. The member 22 is provided with the spaced apart, upwardly sloping arms 25, with their upper ends disposed toward one side of the vertical axis or center of the device and hence to one side of the axis of the piston and packing cup; the arms at top are provided with up-standing spaced apart lobes 26 to receive the end of a hand lever 27 therebetween; the hand lever being pivotally held by a suitable pin or bolt 28.

The lever 27 at a short distance removed from its pivotal point is provided with a fulcrum or packing cup engaging means 29 pivotally secured at its upper end at 30 to the lever 27. The means 29 preferably consists of a clevis member 31 which straddles the lever and is pivoted thereto, while the lower end is preferably provided with a threaded shank onto which a cup or socket member 32 is screwed to permit adjustment; the cup or socketed member 32 being provided with a rubber cushion or plug 33 for engagement with the outer face of the packing cup 19.

In order to guide the mechanism and induce the semi-circular flange 23 to properly enter the groove or channel in the lubricator ring 17, I provide the device with a substantially semi-circular band or plate 34 which is secured to the arms 25 by means of small brackets and bolts as at 35;

the bolts extending loosely through arms 25 so as to permit them to flex upwardly and the bolts are provided with small coil springs which exert a yielding downward pressure on the band or plate 34. The strip or band 34 is arranged at a slight tilt upwardly toward the open side of the device, as shown in Figure 1, to accommodate itself to the arcuate formation of the piston head and packing cup; the band 34 being arranged at a distance above the flange 23 of the member 22 commensurate with the distance between the open or vacant channel 24 in lubricating ring 17 and the top of the cup 19. The plate or band 34 slides onto the top of the packing cup and provides a wide bearing surface on the cup and aligns the flange 23 with the groove or channel in the lubricator ring 17. The member 22 is slid completely about one-half of the piston and cup, causing the rubber cushion or plug of the fulcrum means 29 to engage with the center of the cup. The lever 27 is then pressed downwardly, thereby causing the flange 23 to exert upward pressure on the lubricating ring 17 located beneath or adjacent the curled edge of the packing cup and induces the curled perimeter at one side of the cup to slip out of the recess or groove in the piston thereby completely releasing the cup and lifting the cup and the lubricator ring 17 off the piston at the same time. As previously stated, the plate 34 is yieldingly held in place by the loosely mounted bolts surrounded by small coil springs, with the result that the plate 34 exerts a yielding pressure on the packing cup and accommodates itself to any slight inaccuracies. The end of the lever is pivoted to one side of the vertical center of the device at a point sufficiently removed from its perimeter, which ensures a gradual release of the packing cup at one side of the piston head and prevents the cup becoming damaged.

With this device removal of the cup 17 can be easily accomplished without injury to the cup or to the piston; the removal operation being performed by a single operator in a materially

shorter period of time than has heretofore been the case.

The exemplification shown and described is believed to be the best embodiment of the invention, but modifications in certain details are possible and may be made without, however, departing from the spirit of my invention as defined in the appended claim.

This application refers to the divisible subject matter of my pending application Serial Number 252,286 for "AB air brake piston dismantling device" in keeping with reservation made therein.

What I claim is:

A device for removing the packing cup on the pressure head of an AB air brake cylinder piston comprising a substantially semi-circular band with inwardly disposed flanges about its upper and lower edges, the lower flange being adapted to edgewise engage in an annular recess of the piston head beneath the perimeter of the packing cup, while the upper flange is adapted to extend across the curled perimeter of the packing cup, said upper flange having upwardly and inwardly curving converging arms united at the vertical axis or center with a central opening therethrough and having spaced apart lobes offset from the vertical center; a substantially semi-circular and upwardly sloping guide plate arranged beneath said arms and adapted to rest on the packing cup; means whereby said guide plate is yieldingly supported from said arms; a hand lever pivotally mounted at one end between said lobes with the free end of the lever disposed toward the open side of the piston head engaging band; and an adjustable fulcrum member, provided with a cushion element, disposed through said central opening and pivotally secured to said lever at a point removed from the pivoted end of the lever and adapted to engage the packing cup centrally in a vertical plane removed from the plane of engagement between the band flange and perimeter of the cup.

JOSEPH R. LINDROTH.
